UNITED STATES PATENT OFFICE.

JOHN MCRAE WERTH, OF CEREDO, WEST VIRGINIA.

RAIL-JOINT SUPPORT.

1,315,063.

Specification of Letters Patent. Patented Sept. 2, 1919.

Application filed July 12, 1918. Serial No. 244,612.

To all whom it may concern:

Be it known that I, JOHN MCRAE WERTH, a citizen of the United States, and a resident of Ceredo, in the county of Wayne and State 5 of West Virginia, have invented certain new and useful Improvements in Rail-Joint Supports, of which the following is a specification.

My invention relates to improvements in 10 rail tie plates and it consists in the construction and arrangement herein described and claimed.

The principal object of my invention is to provide a tie plate for rails, arranged to be 15 placed under the ends of a pair of abutting rails to prevent the loosening of the joint and the bending down of the ends of the rails.

Another object of the invention is to provide a rail joint support which will keep the 20 ends of a pair of abutting rails from bending down and consequently eliminate the objectionable "knocking" when the wheels of a train pass over the joint.

25 Other objects and advantages will appear in the following specification, reference being had to the accompanying drawing in which:

Figure 1 is a cross section of a rail joint 30 illustrating the application of the invention,

Fig. 2 is a diagrammatic view showing how the abutting ends of a pair of rails are supported in the middle of the improved joint support, thus preventing the ends of 35 the rails from becoming knocked or bent down,

Fig. 3 is a plan view of the joint support illustrated in Fig. 1, and

Fig. 4 is a plan view of a joint support of 40 a slightly different construction.

The abutting ends 1 at the joint of a railroad rail are centered in the rail joint supporting plate 2 which constitutes my invention, as diagrammatically illustrated in Fig. 45 2. The rail joint support 2 is intended to be as wide as the tie 3.

A transverse recess 4 receives the base of 50 the rail. Recesses 5 disposed laterally of the recess 4 and also running transversely of the support 2, receive the angle bars 6 which include portions that bear against the head of the rail as shown in Fig. 1. The recesses 5 are in a plane above the recess 4.

The shoulders formed between the recesses 55 4 and 5 and the shoulders 7 formed between the recesses 5 and the ends of the support 2

are square as shown and thus form firm support for the base of the rail and the ends of the angle bars 6 respectively. Rail spike holes 8 are formed in that portion of the support 2 in the plane of the recesses 5 in offset relationship. The supporting plate 2 is fastened on the tie 3 by means of spikes which are driven through these holes as will be readily understood from the drawing. 65 These same spikes also hold the angle bars 6 in place.

Much can be said regarding the advantages of this device. It is common knowledge that the lack of a support beneath the 70 ends of a pair of rails and the joint, causes the objectionable "knocking" when the wheels of a train pass over the joint because of the fact that the ends of the rails, being unsupported as stated, are gradually knocked or 75 bent down so that a depression at the joint is made. The rail joint supporting plate 2 is intended primarily to support the ends of the pair of rails at the portion indicated by the arrows in Fig. 2. It will be readily 80 understood that the ends of the rails can never be bent down so long as the support 2 remains beneath.

The rail joint support 2 extends the base of the rail over a considerably greater surface on the tie 3, in effect. When the parts are assembled as illustrated in Fig. 1, a firm and very strong rail joint is provided. The support 2 prevents the rail from spreading outwardly and contributes largely toward 90 the prevention of the loosening of the bolts at the joint, since the rail is held more rigid and free from vibration.

Referring briefly to the modification shown in Fig. 4, it is to be observed that this 95 consists simply of a diminishing of the breadth of the recesses 5 so that the spike holes 8 that are farthest from the center occupy places in the abutment 7 instead of in the plane of the recesses 5. The two forms 100 of the rail joint support shown in Figs. 3 and 4 are intended simply to accommodate different types of angle bars 6.

While the construction and arrangement 105 of the rail joint support as illustrated in the drawing is that of a generally preferred form, obviously slight modifications in the construction may be made without departing from the spirit of the invention or the scope of the claim.

I claim:

A simple-casting rail joint support, con-

sisting of a plate substantially of the width of a tie, with shoulders running transversely at the extremities, recesses forming angle bar planes located below said shoulders at 5 right angles to the abutting surfaces thereof, said planes being relatively broad to provide ample bases for angle bars; and a rail base recess in a plane below said angle bar

planes with right angled shoulders to be engaged by the edges of the rail base, said angle bar planes being staggeredly apertured to enable certain spikes to be driven close to the rail and others toward the extremities of the angle bars, to provide an equally distributed fastening for all parts.

JOHN McRAE WERTH.
